UNITED STATES PATENT OFFICE.

HENRY SCHERFF, OF SOUTH KAUKAUNA, WISCONSIN.

LIFE-SAVING DETACHABLE DECK.

1,101,336.

Specification of Letters Patent. Patented June 23, 1914.

Application filed June 17, 1913. Serial No. 774,184.

To all whom it may concern:

Be it known that I, HENRY SCHERFF, a citizen of the United States, residing at South Kaukauna, in the county of Outagamie and State of Wisconsin, have invented 5 new and useful Improvements in Life-Saving Detachable Decks, of which the following is a specification.

This invention relates to improvements 10 in ships and other vessels and especially with reference to the provision of a detachable and buoyant deck which ordinarily serves as a hurricane or upper deck on a ship or other vessel and which is adapted to be 15 detached therefrom and caused to float in the event that the vessel should sink, and thus enable the detachable deck to be used as a means for saving the lives of persons on the vessel, the invention consisting in 20 the construction, combination and arrangement of devices hereinafter described and claimed.

In the accompanying drawing.—Figure 1 is an elevation of a vessel provided with 25 an upper, detachable buoyant deck constructed in accordance with my invention. Fig. 2 is a plan of the same. Fig. 3 is a vertical sectional view of the upper portion of the same and of the buoyant detachable 30 deck. Figs. 4 and 5 are detail views.

In accordance with my invention, the vessel 1 which is here shown as a steamship is provided with horses 2 that rise from its sides or bulwarks and which serve to support 35 my improved detachable buoyant upper deck 3 at a suitable distance above the main deck 4 of the vessel.

My detachable deck may correspond in width with the vessel or substantially so but 40 is of less length than the vessel so that it terminates short of the bow and stern. Its front and rear ends are preferably rounded as here shown and my improved deck 3 is provided with a rail 5 which extends around 45 its ends. The deck 3 is provided with an opening 6 large enough to substantially clear the smoke stacks 7 of the vessel and the said opening is also railed as at 8.

My improved detachable and buoyant 50 deck comprises a top or true deck 9 and bottom 10 and side and end walls 11. The frames 12 of my improved detachable and buoyant deck are preferably of open construction and made of steel and a steel net-work or foraminous fabric 13 is stretched 55 over the tops of the said frames and the deck

or top 9, which is preferably made of galvanized sheet iron or other like material, is placed on the network 13 and riveted to the frames 12 through the net work, the latter serving to support the deck or top 9 at the 60 portions above the spaces between the said frames 12 and prevent the top or deck 9 from being injured by persons standing or walking thereon. This construction of the improved deck makes the same exceedingly 65 strong and durable as well as extremely light, considering its size and prevents the deck from making the vessel top heavy. The sides and bottom of the improved deck are 70 also preferably made of sheet or plate iron or steel of suitable thickness and are provided on their outer sides with strips 14 of iron or the like and also with an outer covering of asbestos as at 15, air space being 75 thus formed between the asbestos outer covering or armor and the sides and bottom of the detachable and buoyant deck to protect the latter from heat, as when the vessel on which the deck is used should be on fire. 80

My improved detachable and tapered end deck is also preferably provided with a rudder as at 16, a propeller 17 and a suitable motor 18 for driving the propeller at least 85 a sufficient length of time to get the deck out of the vicinity of the sinking ship when the deck has been detached therefrom. The deck may be provided with suitable hatches 18' and compartments 19.

The deck 3 is provided at the bottom with 90 cross beams 20 the ends of which project beyond the sides of the deck and are adapted to rest in notches or sockets 21 in the upper sides of the supporting horses or stanchions 2. The horses or stanchions are also provided with pivoted catches 22 having openings to receive the ends of the said beams. Ordinarily, these catches will be kept in engagement with the beams to lock the latter 95 and the deck on the stanchions or horses and 100 thus keep the deck securely fastened above the vessel and prevented from working loose during storms or in rough weather but in the event of a disaster which makes the use of the detachable and buoyant deck necessary 105 the catches 22 will be cast off from the beams 20 so that should the vessel sink the deck 3 with the persons thereon would continue to float and thus enable the lives of 110 the ship's company to be saved.

I claim:

1. A vessel having stanchions extending

upwardly from the sides thereof, said stanchions having recesses in their upper ends, and a buoyant deck having cross beams at its bottom, the ends of which cross beams project beyond the sides of said buoyant deck and rest in the recesses of the stanchions so that the buoyant deck is supported in elevated position upon the vessel by the stanchions and cross beams, and means to detachably secure said cross beams to the stanchion.

2. A detachable and buoyant deck structure for use on vessels and provided with a fire resisting armor spaced from its bottom and sides.

In testimony whereof I affix my signature in presence of two witnesses.

HENRY SCHERFF.
